UNITED STATES PATENT OFFICE.

FREDERICK CHADWICK, OF HAMILTON, CANADA.

CLUSTER OUTLET FOR ELECTRIC LAMPS.

Application filed December 10, 1926. Serial No. 153,863.

The invention relates to improvements in cluster outlets for electric lamps, consisting of a shell comprised of upper and lower sections, a bracket unit in the lower section 5 of the shell and having means for attaching to the lamp pedestal or column, combined means for securing the upper section and lamp shade to the lower section, and pivoted adjustment devices on said bracket, to 10 which are secured the nipples for the lamp sockets.

The principal object of the invention is to provide a cluster outlet having means for the adjustment of the angle of the lamps, 15 and another important object is to materially reduce the number of parts forming such a structure.

A further object is to provide means for the combined purpose of securing the upper 20 section of the cluster outlet to the lower section thereof and for securing the usual lamp shade in a single operation.

Another object is to provide a device of the class specified which will be simple, 25 durable, efficient, and inexpensive to manufacture.

These, together, with other objects, may be attained by the construction, combination, and arrangement of the parts as will 30 be hereinafter more fully described, illustrated in the accompanying drawings, and ascertained in the claim hereunto annexed.

Referring to the drawing:

Figure 1 is a front elevation of the improved cluster outlet;

Figure 2 is a cross-sectional front elevation of Figure 1 constructed in accordance with this invention;

Figure 3 is a cross-sectional elevation of 40 the same taken on the line 3—3 in Figure 1;

Figure 4 is a top view of the cluster outlet with the upper section of the shell removed;

Figure 5 is a perspective view of the bracket unit;

Figure 6 is a front or face view of the adjustment device;

Figure 7 is a side view of the adjustment 50 device; and,

Figure 8 is a top view of the adjustment device.

Similar reference numerals refer to corresponding parts throughout the several 55 views.

This invention relates particularly to clus-

ter outlets of household table and floor (piano) lamps. The current translating wires are usually led through the core of the pedestal or column of the lamp, mounted upon which is the cluster outlet, the subject-matter of this invention, and from within this cluster outlet said wires are distributed to the lamp sockets. These cluster outlets are in the form of a shell comprised of a 60 lower section 10 and an upper section 11, which, when in use, are united. The usual lamp shade is supported upon the upper section 11, the web or spokes of the lamp shade frame being shown on the drawing in dotted 65 lines indicated at 12.

Referring to the invention. In the bottom of the lower section 10 is an opening 13 to receive the usual nipple on the top of the lamp pedestal. In the interior of this 70 section 10 is a bracket unit comprised of a perpendicularly disposed ear 14, a horizontally disposed foot plate 15 formed as one with the ear by bending the material, and a horizontally disposed arm 16 formed by 75 cutting the material of the ear 14 to the required form and bending outwardly the cut-out portion.

The foot plate 15 is mounted upon the bottom of the lower section 10 and the entire 80 bracket unit is secured in place by the rivet 17, or other suitable device. In this foot plate a hole is formed and the material about the hole is drawn upwardly and threaded 85 on its interior as at 18 to receive the lamp pedestal nipple. Thus when the bracket unit is tightened by screwing down on said nipple the lower shell section 10 is made fast to the lamp pedestal.

On the lateral portions of the ear 14 are 90 mounted the pivoted adjustment devices. These devices are each comprised of two flat circular plates 19 and 20 disposed at substantially right angles and united by an elbowed neck portion 21 formed as one therewith. 100 The plates 19 are pivoted to the said lateral portions of the ear 14 by the bolts 22, or by rivets, as preferred. Around the openings for the passage of said bolts or rivets in each of these plates is an annular plurality 105 of rounded protuberances 23 which may be formed, as for example, by indenting the opposite side of the plates. These protuberances engage corresponding recesses 24 in the ear 14, which may be formed by indenting the latter.

The plates 20 are provided with threaded

nipples 25, to which are adapted to be secured the usual electric lamp sockets, and through which extend the feed wires to these sockets. These nipples extend through slots 26 in the lower shell section 10. The pivoted adjustment devices, together with the nipples 25, by pressing on the latter, may be rotated relative to the ear 14 for the purpose of adjusting the angle of the electric lamps. When the desired angle is obtained, the specific adjustment is maintained by the resistance of the engagement of the protuberances 23 with the recesses 24 on the ear and a spring washer 22^a interposed between an outer washer 22^b and the plate 19. While adjusting, the spring washer 22^a gives to allow the protuberances to leave the recesses and pass over the surface of the ear. To the arm 16 is secured a perpendicularly disposed stud bolt 27. This bolt extends through an opening in the top of the upper shell section 11, through the lamp shade frame 12, both said section and shade being made rigid by screwing down the usual ornamental cap nut 28.

There has thus been produced a simple and useful device of the class described and for the purpose specified, and now having fully described the invention and the manner in which it is to be performed in such manner that any person skilled in the art to which it appertains could make the same, what is claimed as new, is:—

In a cluster outlet, a shell, a bracket unit in the shell comprised of a foot plate secured to the bottom of the latter and a perpendicular ear extending from the foot plate and an arm extending horizontally from the ear, said foot plate being provided with means for attachment to the pedestal of a lamp, adjustment devices on said ear adapted for adjustment to varying angles, lamp socket nipples secured to said adjustment devices and extending to the outside of said shell through slots therein, and a stud bolt extending perpendicularly from said arm through the top of the shell.

In testimony whereof I have affixed my signature.

FREDERICK CHADWICK.
